UNITED STATES PATENT OFFICE.

BENJAMIN BARTON SHARP, OF SAN FRANCISCO, CALIFORNIA.

ALTITUDE-INSTRUMENT.

SPECIFICATION forming part of Letters Patent No. 333,555, dated January 5, 1886.

Application filed March 31, 1885. Serial No. 160,832. (No model.)

To all whom it may concern:

Be it known that I, BENJAMIN BARTON SHARP, a resident of San Francisco, State of California, have invented a novel and useful 5 Anglemeter; and I hereby declare that the following is a full, clear, and exact description of the same, reference being had to the accompanying drawings.

My invention relates to a novel means for 10 measuring altitudes and ascertaining time during day or night.

The following description fully explains the nature of my said invention, and the manner in which I proceed to construct, apply, and 15 use the same, the accompanying drawings being referred to by figures and letters.

Figure 1 represents the stern of a vessel, showing the position of the anglemeter. Fig. 2 is an enlarged view of the anglemeter 20 mounted. Fig. 3 is a plan view of the anglemeter. Fig. 4 represents elevation of the cross-bar, showing spirit-levels. Fig. 5 is a plan view of the same. Fig. 6 is an enlarged view of the anglemeter, showing index-bar 25 and nonius or vernier. Fig. 7 is an end view of the telescope, showing eye-piece and shade.

The stern of a boat is represented in Fig. 1 by the letter *a*. Upon this is shown the stand and anglemeter at *b*.

30 My device, which I call an "anglemeter," *b*, consists of a graduated arc, *b*^x, of ninety degrees, having an index-bar, *l*, and nonius or vernier *n*, tangent-screws *o* and clamp, and a telescope, *m*, attached to the face of the index-bar, and having an eye-piece, *g*, and shade *r*, and a cross-wire at its farthest extremity. The telescope is held to the index-bar by bands *m*^x, having set-screws *p*^x, by means of which the telescope may be revolved and held 40 in place. The anglemeter is mounted upon a movable hollow frame or stand, *c*, of conical or pyramidal form, and of a suitable height and diameter. In the center of this frame a pendulum, *d*, swings out and in the openings *e* on both sides of the lower part of the frame.

45 The pendulum is attached to a cross-bar, *t*, through which a shaft, *h*, extends. On each of the cross-bars there is a lug, *k*, the horizontal flange of which is screwed to the cross-bar, and the vertical flange is perforated for the 50 adjusting-screws *p*^x, attached to the anglemeter and acting in the slots *p*. The face of the

cross-bar is rabbeted, *j*, for a slide and rest for the anglemeter on the upper surface of the cross-bar, and on its end there are spirit-levels 55 *i*. A metallic ring, *f*, plays and rotates in a groove in the upper part of the frame, and within this ring there is another, *g*, pivoted to *f*, and is adjusted as to using and oscillates like a mariner's compass on its gimbals. 60 The inner ring, *g*, is notched for the gimbals of the shaft *h* to act, and it is adjusted to a horizontal position by the pendulum and its plane determined by the spirit-levels, Fig. 3.

This novel instrument combines perfect 65 means for measuring altitudes. The entire field may be obscured, as the slots in both arms of the anglemeter, provided with adjusting-screws, permit the instrument to be attached by either of its radial limbs, and to 70 allow a slight movement on the adjusting-screws by means of the slots *p* in said limbs.

The adjustments of the instrument are so nice and accurate that after making an observation it is impossible to place the angles 75 out of order.

After use, the anglemeter is removed to the cabin, where it is read and the result of the observation obtained, and the instrument is secured until it is again wanted. The frame 80 may be removed or remain on deck under cover.

The anglemeter is an angle of ninety degrees, which describes that arc of the heavens representing the horizontal limb, and of course 85 the perpendicular limb—that is to say, the zenith. The vision is directed from right angle toward any part of the arc of ninety degrees, as seen direct from that angle, and the true altitude is at once obtained, less the sum 90 of atmospheric refraction. There is no dip of the horizon, whatsoever the elevation of the eye above the surface. The center of the object is taken as readily as either limb, and consequently there is no semi-diameter. The 95 apparent difference of position of the object or its parallax is of small moment, as amounts to only a few seconds in the case of a large altitude.

Having thus fully described my invention, 100 what I claim, and desire to secure by Letters Patent, is—

1. In an anglemeter, the combination of the frame or stand having the rings *f* and *g*, mov-

able as described, a cross-bar, *t*, swung in ring *g* by means of a shaft, *h*, a pendulum attached to said cross-bar below and a graduated arc, and radial limbs having a nonius or vernier, 5 *n*, index bar *l*, and telescope *m*, secured adjustably to the upper side of the bar *t*, as set forth.

2. In an anglemeter, the combination, with the stand having the rings *f* and *g*, as described, and the cross-bar *t*, having the shaft *h*, by means of which it is swung in the ring *g*, and provided with the spirit-levels *i* and lugs

k on top and the pendulum beneath, of the graduated arc having the two radial limbs at ninety degrees from each other, provided with 15 slots *p*, adjusting-screws for connecting the radial limbs to lugs *k*, and the vernier *n*, bar *l*, and telescope, as described.

In testimony whereof I have hereunto set my hand and seal.

BENJAMIN BARTON SHARP. [L. S.]
